3,075,201 HEADBAND ASSEMBLY FOR WELDER'S HELMET

Frank W. Lindblom, Warwick, R.I., assignor to Welsh
Manufacturing Company, a corporation of Rhode Island

Filed Dec. 9, 1960, Ser. No. 74,936
5 Claims. (Cl. 2—8)

This invention relates to a welder's helmet more particularly to the headband assembly and its connection to the shield.

A welder's helmet usually consists essentially of a band to extend about the head and over the top of the head and a shield which is so mounted on this band that it may be raised from a position in front of the face to a position above the head as occasion may require. The adjustment of the headband and its connection to the shield heretofore has been somewhat adjustable but not adjustable to the extent desired.

One of the objects of this invention is to provide a headband which will be adjustable to many positions additional to the positions to which headbands heretofore used have been capable.

Another object of the invention is to resiliently mount the shield on the headband so that should the shield be struck there will be some give before applying pressure upon the head.

Another object of the invention is to simplify the heretofore separable parts by molding a single unit so that it may be utilized for several functions, such for instance as is required in the adjustment of the encircling size of the headband.

Another object of the invention is to provide a device which will have few metal parts, most of the parts being of a known non-metallic molded construction which may be made in multiple which are durable in use and which are more pleasing to contact with the head than metal parts and are also of a lighter weight when worn.

With these and other objects in view, the invention consists of certain novel features of construction as will be more fully described and particularly pointed out in the appended claims.

In the accompanying drawings:

FIG. 1 is a perspective view showing the headband assembly and the shield of a welder's helmet indicated in dot-dash lines as it would be associated with the headband;

FIG. 2 is a sectional view through the connection at one side of the headband showing its connection to the shield;

FIG. 3 is a side elevation of a fragmental portion of the headband with the shield removed and showing the part which connects to the shield in full lines when in its lower position but in dotted lines in the position which it assumes when the shield is raised;

FIG. 4 is an exploded view of parts of the pivotal mounting between the headband and the shield showing the relation of the parts;

FIG. 5 is a perspective view of the two overlapping end portions of the encircling part of the headband;

FIG. 6 is a top plan view of the headband with the shield omitted illustrating the adjustment for the encircling size of the head;

FIG. 7 is a sectional view through the arcuate sleeve showing the gear and rack arrangement for expansion of the headband;

FIG. 8 is a section on line 8—8 of FIG. 7; and

FIG. 9 is a perspective exploded view of the parts of the headband adjusting means.

In proceeding with this invention, I have provided a headband consisting of a head encircling portion and a

2

cross strap for over the top of the head. The head encircling portion is made in two parts so that an adjustment may be had as to alignment between the part extending around the back of the head and the part extending about the front of the head. I have also arranged a more simple form of encircling size adjustment between the back part which is formed in two pieces. I have also arranged a different mounting for the shield which is pivotally related to the headband by forming a resilient piece pivoted on the headband but detachably connected to the shield, the arrangement being such that four different positions may be had between the pivotal mounting and the shield for adjustment while the bracket which is attached to the shield may also be adjusted with reference to the shield. Further I have molded the gear and handle and also the ratchet connection to a spring washer all in one piece so that there is a simplification of assembly in the gear and rack type of adjustment for encircling size of the headband.

With reference to the drawings 10 designates generally the headband assembly as shown in FIG. 1 which consists of a head encircling band comprising a front portion 11 for extending around the forward part of the head with two arms 12 and 13 extending upwardly from the ends of this front portion and overlap with a series of holes 14 in the arm 12 and a projection 15 on the part 13 to enter one of these holes so as to provide varying sizes or lengths of the arms 12 and 13 which extend over the top of the head. An integral loop 16 is formed on the part 12 encircling the part 13 which slides there through so as to provide a guide. The rear portion of the encircling band is designated generally 17 and comprises two parts 18 and 19 which are adjustably held in a sleeve 20 which will be more fully explained. The rear portion 17 is pivoted to the front portion 11 as will be further referred to. The end portions of the two parts 18 and 19 are provided with a series of openings 21 which extend laterally of the width of the band 18 or 19 so as to receive within one of these openings a pin 22 (see FIG. 5) so that the rear portion of the band designated generally 17 may be swung about its pivot to be held either in the central plane of the front portion 11 of the band or it may be swung about its pivot above or below this plane by the positioning of the pin 22 in a selected one of the openings 21.

The pivotal arrangement of the front and rear portions of the band cooperates with the mounting of a shield designated generally 23 as seen in FIG. 1. The pivotal arrangement between the front and back parts of the encircling band, as shown in FIG. 4, comprises a boss 24 which extends outwardly from a location near the end of the front portion 11 of the encircling band. This being of a plastic construction, the boss is integral therewith. Each circular boss 24 extends through the circular opening 25 (FIG. 2) of the back part 18 or 19. Thus there is a free pivotal movement of the back part with reference to the front part of the encircling band about the boss 24 except as it is limited by the hole and pin connection 21 and 22.

The boss 24 has an integral square projection 26 (see FIGS. 2 and 4) extending outwardly therefrom and also an integral pin or trunnion 27 flattened as at 28 extending further outwardly. These integral parts serve to pivotally mount the shield as will now be explained. Assembled on the squared boss 26 there is a washer 29 (see FIGS. 2 and 4), the square opening 30 of which fits the squared boss 26 so as to prevent relative rotation of this washer on the boss. A recess 31 (see FIG. 2) is also formed in this washer so as to extend over the cylindrical surface 24 of the boss and engage the rear portion of the encircling band 19 so as to provide some friction upon it although permitting it to be pivotal about this boss.

3

The washer 29 carries a radially outwardly projecting stop 32 as may be seen in FIG. 4. There is a bracket 33 which has a bearing opening 34 which is rotatably received upon the trunnion 27 and this bracket is provided with a finger 35 which in its swinging movement will engage the abutment 32 and thus limit the movement of the bracket about its pivotal mounting on the trunnion 27. This bracket is also provided with a plurality of openings 36 to receive in any one of these openings a pin 37 which projects inwardly from the inner surface of the shield 23. See FIG. 4.

A mounting loop designated generally 40 consists of a closed plastic band-like member having a bearing opening 41 in the middle part of the inner portion 42 thereof which bearing opening 41 is rotatably mounted on the trunnion 27 so as to rotate freely thereabout, and in order to secure this inner portion in position a nut 43 is provided to engage one surface of this portion 42, the nut being prevented from rotation by having flats thereon to engage the flattened surfaces 28 of the trunnion 27. This nut is threaded so as to receive the screw 44 having its head 45 fitting into the recess of the boss 24 so that it will be removed from the inner surface of the band which engages and embraces the head. This loop 40 has an outer portion 46 from which there projects outwardly a squared boss 47 which is located eccentric to the pivotal mounting of the portion 42 of this loop and as shown in FIG. 2 this boss 47 is above the center line of the screw and pivotal mounting of the portion 42. The shield 23 is provided with an opening 48 also of square shape and of a size to closely fit the squared boss 47 and is shown in FIG. 2 as being received on this boss when this boss is in its upper position such as shown in FIG. 1. However, if it is desired that the shield be mounted in a lower position, the loop 40 may be rotated through 180° about its pivot on trunnion 27 so that the squared boss 47 will then be below the pivotal axis and will be as shown in dot-dash lines for the loop 40 and the boss 47 in FIG. 2. It will also be apparent that if this loop is rotated through 90°, then the boss 47 will be on the horizontal center line of the pivot so as to provide an intermediate mounting as to relative height of the shield and headband. A cotter pin 49 passing through an opening in the boss 47 secures the shield in assembled position. The loop 40 is made of plastic material and is resilient or compressible so that its opposite portions 42 and 46 may be resiliently moved toward each other. This provides a shock absorbing medium for the shield when so mounted so that should a blow be received on the shield, it will be transmitted to the head only through this resilient mounting which will absorb some of the shock.

The shield 23 is of a generally arcuate shape in a horizontal plane and is of a hard plastic material and though it is relatively rigid, there is an opportunity for some expansion of the wings 23' of this shield so that they may spread away from each other and will then return back to normal position under the inherent tendency of this shield to again contract. Advantage is taken of this fact in the connection between the shield and the headband assembly. Thus, the shield may have its wings 23' sprung apart so that its openings 48 may snap into position over the squared boss 47 and at the same time the shield may be adjusted as to its relative position on the bracket 33 by having its pins 37 snap into the selected openings 36 in this bracket. Thus the bracket and resilient loop 40 are so mounted that the shield may be lifted from the position shown in FIG. 1 to a position above the head by merely engaging the lower portion of the shield and swing it upwardly. This causes the bracket 33 and the resilient mounting loop 40 to swing upwardly from the position shown in full lines in FIG. 3 to the position shown in dotted lines. It is usual for the welder, when he desires to lower the shield to merely shake his head forward coming to a sudden stop so that the momentum of the shield will cause the shield to

swing downwardly from the raised position into a vertical position before the face, and in order that the shield will stop at the desired position in front of the face and in a vertical position, the abutment 32 on the washer 29 is so arranged on the headband that when the arm 35 of the bracket 33 engages this abutment, the shield will be in the correct position which position is shown in full lines in FIG. 3. Thus it will be apparent that the bracket moves from the dotted line position in FIG. 3 to the full line position in FIG. 3 and there comes to rest by engagement between the stops.

The encircling size of the headband which essentially consists of an adjustment between the parts 18 and 19 of the rear portion is shown in greater detail in FIGS. 6 to 9. Here we see an arcuate sleeve 20 which, as shown in FIG. 8, has an outer wall 50 and an inner wall 51. These walls have registering openings comprising a bearing opening 52 in wall 50 and an access opening 53 in wall 51. The sleeve is open-ended and receives the parts 18 and 19 therein. The part 18 is slotted as at 54 and has a plurality of teeth 55 extending downwardly from the upper side of the slot while the part 19 is slotted as at 56 and has a plurality of teeth 57 extending upwardly from the lower edge of the slot. These two strips are in slidable relation and are guided in end to end sliding arrangement by the upper edge walls of the sleeve 20. The openings 52 and 53 are of such a size that the teeth 55 and 57 project into the openings. A gear 58 extends through and has a bearing in opening 52 and engages the teeth 55 and 57 of these racks as may be seen in FIG. 7. This gear 58 is a part of a larger unit designated generally 59 (FIG. 9) which includes a handle 60 on the inner surface of which there are a plurality of radial ribs 61. On the outer surface of this sleeve 20 there is mounted a metal washer 62 which has arms 63 extending into recesses in the outer surface of the sleeve 20 so as to hold it against rotation while it has bosses 64 to engage between the ribs 61 and thus hold the unit 59 in the position to which it has been rotated. A washer 65 within the sleeve and registering with the access opening 53 although larger than this opening and of a size substantially the width of the sleeve serves as a centralizing mount for a screw 66 having head 67 in and accessible through the opening 53 and which engages threads of the bore 67' so as to hold the unit 59 in position in the sleeve but with its gear in engagement with the racks of the parts 18 and 19 so as to provide a size encircling adjustment for the headband assembly. It will thus be apparent that turning the handle 60 in one direction will expand the encircling headband size while turning the unit or handle 60 in the opposite direction will contract the encircling size. A more contracted size is shown in dotted lines in the plan view shown in FIG. 6. The above provides for a much simpler assembly than heretofore.

I claim:

- 55 1. In a welder's helmet, a headband member, a shield member and a mounting means independent of said members, said mounting means being pivotally secured to one of said members to swing about a pivotal axis and secured to the other member to move therewith as relative movement between the two members is had, said means being resilient in the direction of the pivot axis and said mounting means being a closed loop having its opposite sides resiliently movable toward each other.
- 56 2. In a welder's helmet as in claim 1 wherein said mounting means is pivoted on said headband centrally of said loop on one side thereof and is attached to said shield member by means adapting the loop to be reversed with respect to the shield to change the relative position of the shield with respect to its pivot.
- 57 3. In a welder's helmet, a head supporting assembly comprising a head encircling band having two overlapping parts with elongated registering slots, a sleeve generally rectangular in cross section embracing said slotted parts and having a bearing opening in the outer wall and an access opening in the inner wall registering with

the bearing opening, rack teeth on the edge of one slot looking toward rack teeth on the opposite edge of the other slot, a unit having a reduced portion journaled in said bearing opening and having a threaded bore comprising a gear meshing with said opposite rack teeth and a handle to turn the gear for adjusting the encircling size of the band, a washer within the sleeve of a size larger than the width of the slots and a screw in said bore having a head engaging said washer and said head being accessible thru said access opening.

4. In a welder's helmet as in claim 3 wherein the washer is of a size to engage the opposite edge walls of the sleeve and serves to centralize the unit.

5. In a welder's helmet as in claim 3 wherein the gear

teeth are of a size to bear in the bearing opening of the sleeve.
